UNITED STATES PATENT OFFICE

111,296

DESIGN FOR A COMBINED DIAL AND HANDS FOR A CLOCK OR SIMILAR ARTICLE

Henry A. Barge, La Crosse, Wis.

Application April 26, 1938, Serial No. 76,759

Term of patent 14 years

To all whom it may concern:

Be it known that I, Henry A. Barge, a citizen of the United States, residing at La Crosse, in the county of La Crosse and State of Wisconsin, have invented a new, original, and ornamental Design for a Combined Dial and Hands for a Clock or Similar Article, of which the following is a specification, reference being had to the accompanying drawing, forming part thereof.

Figure 1 is a perspective view of a combined dial and hands for a clock showing my new design.

Figure 2 is an upper edge view.

The hour hand shown in broken lines is co-operable with the dial in such a manner that it gives the appearance of the central figure operating a pointer. The minute hand, which should be similar to the hour hand except for its length, has been omitted for convenience of illustration.

I claim:—

The ornamental design for a combined dial and hands for a clock or similar article, as shown and described.

HENRY A. BARGE.
